UNITED STATES PATENT OFFICE.

JACQUIN M. C. BRANCO, OF SOMERSET, MASSACHUSETTS, ASSIGNOR OF ONE-HALF TO
JAMES K. LANNING, OF FALL RIVER, MASSACHUSETTS.

MACHINE FOR BRAIDING ELASTIC FABRICS.

Application filed July 27, 1926. Serial No. 125,301.

This invention relates to a machine for braiding elastic webbing and is intended to provide a construction for such machine that will enable it to produce a stronger and more elastic fabric than is produced on machines of this class as heretofore constructed.

Heretofore it has been the practice to lead a series of elastic cords from a common revoluble spool to a common braiding point or eye above the machine, relying upon frictional resistance to the rotation of said spool to produce tension upon the cords, but I have found that this arrangement results in unequal stretch of the different elastic cords and produces an imperfect fabric.

One of the features of the present invention resides in an arrangement which secures equal and uniform tension on all the elastic cords entering into the fabric, with the result that the webbing produced is not only stronger but also much more elastic or stretchable. The tensioning members may be also arranged to cause the machine to stop whenever one of the elastic cords is broken, thereby preventing the production of imperfect webbing lacking one or more strands of elastic cord. These and other features of the invention will be particularly explained in the following specification and will be defined in the claims hereto annexed.

In the drawings I have illustrated the preferred form embodying the principles of this invention, in which:

Figure 1 is a front elevation showing so much of a braiding machine equipped with my improvement as is necessary to an understanding of my invention.

Figure 2 is a plan view of the top plate or track plate of a braiding machine, the carriers being removed, in association with a portion of the stop mechanism.

Figure 3 is a plan view of the stop-mechanism releasing-lever detached from the machine and associated with the annularly arranged cord-guiding members.

Figure 4 is a side elevation showing a portion of the stop mechanism for stopping the machine.

Figure 5 is a detail view, partly in vertical section, showing the course of an elastic cord in association with its tensioning member.

Generally speaking, the invention embodies a construction acting to maintain a

uniform and equal tension on each of the elastic cords that are incorporated into the elastic fabric so that all the cords will stretch equally and afford an equal resistance to the stretching action, thereby increasing the strength of the fabric. As shown in the drawings, the braiding machine is mounted on a raised frame and, so far as may be necessary to an understanding of the present improvement, it comprises an upper bed-plate or track-plate 1, and a lower bed-plate 2, spaced apart in horizontal planes by interposed sleeves 2^a, through which the usual fastening bolts are passed. The upper or track plate is provided with two sinuous or serpentine grooves or tracks 1^a, 1^b, in which is guided a traveling carrier 3, having a downwardly projecting pin 3^a, to be engaged by actuating cams 3^b, which are rotated by suitable trains of gearing 3^c, from the driving mechanism in the usual manner so that a series of yarn bobbins 5, mounted on vertical spindles 4, secured to the traveling carriers 3, may be carried, one set moving in one track in one direction and the opposite set moving in the opposite track in the opposite direction so as to cross each other's paths and produce the braiding action for the yarn ends which are brought together to the braiding point or eye 10. The respective yarn ends α are carried up through suitable guides 6 from the supply bobbins 5 to the braiding eye 10, but the details of this braiding mechanism are not involved in the present invention and, therefore, further detailed explanation thereof is omitted.

A stop member 30 is secured in position to cover the tracks in the foremost or forward section of the machine so that each yarn carrier, when reaching this spot, instead of continuing its travel around and around the bed-plate, reverses itself and travels backward in the other track 1^b, until it reaches the limit of its traverse against the opposite end of the stop 30. This stop is used to braid a flat piece of fabric instead of a tubular piece of fabric which would result in having the carriers circle the machine continuously, each set in one direction.

The elastic cords γ , which are to be incorporated in the braid, are passed up

through the center of each space surrounded by the tracks 1^a, 1^b, and carried to the eye or throat 10 of the braiding guide, in a manner that will now be explained.

5 These elastic cords or filaments *y* are wound on a revoluble spool 7 mounted beneath the machine near the floor in any suitable braiding supports, not shown, so that they may all unwind simultaneously from 10 the spool to pass into the webbing formed by the braiding machine.

15 Heretofore these cords have been passed directly through their vertical guides to the braiding throat 10, it having been supposed that the frictional retardation of the supply spool would produce proper tension for the set of elastic cords. I have found, however, that the lack of perfect braiding of this type 20 of fabric is due to the unequal tensioning of the elastic cords since some of them are stretched more than are others.

25 My present improvement, therefore, involves an arrangement of tensioning means applied to each individual cord in such a way as to make it possible to produce an equal and uniform tensioning of all the 30 cords while at the same time increasing or diminishing such tension according to the particular requirements.

35 With this object in view I provide a ring or annulus 12, supported concentrically with the machine below the lower bed-plate 2, and of smaller diameter or radius than the radial distance of the vertical guide tubes 8 through which the elastic cords *y* travel on 40 their way to the braiding point. In radial relation to each of these guide tubes 8, but offset integrally toward the center, are guide pulleys or rollers 11, best illustrated in Figure 5, over which the respective elastic cords take a quarter turn in their traverse toward 45 their guide-tubes 8. Between these deflecting guide members or rollers 11 and the vertical guide-tube 8, I suspend on each 50 cord a tensioning device which, in this case, comprises a small rod or wire 14 formed, at its upper end, with a narrow fork 14^a, in which is mounted a guide roller or pulley 14^b. At its lower end these 55 vertical tensioning wires pass through guide apertures formed in an arcuate extension plate 15 of a lever 16, which acts indirectly to knock off and stop the driving mechanism, 60 as will be later explained.

55 Continuing upward beyond the track plate 1, is an upright bracket or standard 9, for the most part of semi-tubular construction, which carries, at its upper end, a guide roll 9^a, in approximate alignment with the vertical guide-tube 8, to form a guide from which the elastic cord passes from the braiding throat. For more complete protection the two forward guiding standards, as shown at 9^b, are made completely tubular in form 65 and each have a lateral outlet slot 9^c, through

which the cord emerges and from which it passes over an externally supported guide pulley 9^b, to the braiding throat 10, as shown in Figure 1.

Above and adjacent to the top plate 1 70 is mounted a pivoted lever 18, engaged by a torsion spring 19 which normally throws the rear end of the lever inward, while thrusting the forward end of said lever outward into engagement with a drop latch 75 20 which is provided with a shoulder at 20^a adapted to overhang the adjacent edge of the lever 18 so that the forward end of the lever 18 is normally pressed outward by its spring into retaining position beneath said shoulder 20^a, to prevent the drop latch from falling. The fulcral point of said lever is the screw 18^b.

Pivoted on a horizontal fulcral or pivot pin 16^b, at one side of the machine, 85 is a lever 16, whose upper arm 17 is turned inwardly and preferably notched, as shown at 17^a, to engage the outside face of the lever 18. The lower end of said lever is turned inwardly, as at 16^a, and carries an arcuate 90 plate 15 provided with perforations for the passage of the wires 14 of the cord-tensioning members. To the lower ends of these wires 14, of the tensioning members, are suspended weights 25, each having a central 95 supporting spindle 25^a, to permit putting on or taking off loading weights 25^b, to increase or diminish the weight and the consequent tension or downward pull of the 100 wires 14.

105 Each elastic cord *y* is carried from the spool 7 around its overhead guide pulley 11, through the yoke or fork 14^a and under the roller or pulley 14^b, up through the adjacent vertical guide tube 8, over the pulley 9^a or 9^b, as the case may be, to the braiding throat. The downward pull of the weights 25, which are equal, results in a downward pull or tension upon the horizontal stretch of each elastic cord *y* between its deflecting pulley 11 and its vertical guide tubes 8, so that all cords are stretched equally and uniformly during the operation of the machine. In case any one of the cords *y* should break, there no longer being any support for its tensioning member, the tensioning member drops until its fork, at the upper end, strikes upon the arcuate plate 15, carried by the lower arm 16^a of the lever 16, thereby swinging the upper arm 17 of said lever inwardly and consequently moving inwardly the forward arm of the detent 18 out of engagement with the overhanging shoulder of the drop latch 20, so that the drop latch is permitted to fall, thereby disengaging the driving clutch 22 115 from the compound pinion 24, on the driving shaft 23, and stopping the machine.

120 It will, therefore, be seen that by my improvement two results are secured. In the first place an equal and uniform tension is 130

produced on all the elastic cords entering into the fabric, with the consequence that the fabric has greater stretch and elasticity, and at the same time is stronger than fabrics woven with the cords under unequal tension. In the second place imperfect braiding, due to the breakage of one or more of the elastic cords, is prevented because, as soon as a single cord breaks, the machine stops instead of continuing to braid with one or more of the elastic cords lacking. This result is effectually accomplished by the stop-releasing lever having engagement with each and all of the tensioning members, without disturbing their proper annular order or arrangement, since the stop lever is provided with an arcuate or approximately annular plate which not only forms a guide for each of the drop wires at its lower end, but also forms a yielding stop which is actuated by the impact of the dropping weight to cause the stretch of the machine.

While the invention was originally devised for braiding elastic cords, it will be understood that it is also applicable to the covering by braiding of cords or warp threads of textile fibre, such as cotton, silk or the like since, when applied to warps of such material, it results in producing a covered cord of superior and uniform strength.

What I claim is:

1. In a machine for braiding elastic fabric, the combination with yarn-delivering and braiding mechanism of a carrier for elastic cords, guiding means for each cord to cause the cord to travel for a distance in an approximately horizontal plane as it moves toward the braiding point, and a weight suspended on the horizontal portion of each cord, and stop mechanism arranged to be rendered active by the fall of the suspended weight when its cord is broken.

2. In a machine characterized under claim 1, the combination with a supply spool for the elastic cords located below the braiding mechanism, a deflecting guide member for each cord arranged above the spool to allow the cord to turn to horizontal position, a laterally offset upright guide for guiding each cord to the braiding point, a tensioning member suspended on the cord between the two guides acting to maintain a uniform tension on the cord as it moves to braiding position.

3. In a machine characterized under claim 1, the combination with a supply spool for the elastic cords located below the braiding mechanism, a deflecting guide member for each cord arranged above the spool to allow the cord to turn to horizontal position, a lateral offset upright guide for guiding each cord to the braiding point, a tensioning member of variable weight suspended on each cord between the two guides and acting to maintain the desired tension con-

stantly on the cord as it moves to braiding position.

4. In a machine characterized under claim 1, the combination with a supply spool for the elastic cords located below the braiding mechanism, guide members by which each cord is led to the braiding throat of the machine in laterally offset planes, an annularly arranged series of tensioning weights suspended on the laterally offset portions of the suspended cords, and a releasing lever pivoted on the machine for disconnecting the driving mechanism, said lever being provided with an arcuate lower arm extending beneath the braiding mechanism in position to yieldingly support any tensioning weight that drops from the cord in order to stop the machine when its cord is broken.

5. In a machine characterized under claim 1, the combination with an annular series of tensioning weights suspended on the respective elastic cords that are to enter into the fabric, a lever pivoted to swing about a horizontal axis, the lower arm of said lever being arranged to be depressed when any tensioning member falls from its suspending cord, the upper end of said lever being disposed to engage a clutch-controlling mechanism by which the machine is disconnected from its driving mechanism when any of the elastic cords break and allow the suspended tensioning member to drop and actuate said pivoted lever.

6. In a machine for braiding elastic fabric, the combination with yarn delivering and braiding mechanism, of a series of cord-delivering guides arranged concentrically above the braiding mechanism, a supply-spool carrying a series of elastic cords revolvably mounted beneath the braiding mechanism to supply an elastic cord to each cord-delivering guide, and a series of individual tensioning weights suspended on the respective cords beneath the braiding mechanism, and means energized by the fall of any individual weight for automatically causing the stoppage of the machine.

7. In a machine for braiding elastic fabric, the combination with yarn-delivering and braiding mechanism, of cord-delivering guides concentrically disposed above the braiding mechanism, a supply spool carrying a series of elastic cords revolvably mounted to deliver the cords to their respective delivery guides, a series of individual tensioning wires suspended on the respective cords beneath the braiding mechanism, and removable tensioning weights carried by said wires in order to exert a predetermined but variable tension upon the series of elastic cords.

8. In a machine for braiding elastic fabric, the combination with yarn-delivering and braiding mechanism, of a series of cord-delivering guides arranged about a common centre above the braiding mechanism, a rev-

oluble supply spool carrying plural elastic cords for delivery to the respective delivery guides, a series of individual cord guides arranged below the delivery guides in offset relation thereto, and a series of tensioning weights arranged beneath the braiding mechanism in position to engage the respective

10
cords intermediately of said offset guides and the delivery guides to exert a predetermined tension on the individual cords.

In witness whereof, I have subscribed the above specification.

JACQUIN M. C. BRANCO.
